UNITED STATES PATENT OFFICE.

ALBERT WILLIAMS DAW AND ZACHARIAS WILLIAMS DAW, OF LAURVIG,
NORWAY.

ROCK-DRILL.

SPECIFICATION forming part of Letters Patent No. 447,666, dated March 3, 1891.

Application filed October 12, 1889. Serial No. 326,846. (No model.) Patented in England March 2, 1889, No. 3,691.

To all whom it may concern:

Be it known that we, ALBERT WILLIAMS DAW and ZACHARIAS WILLIAMS DAW, mining engineers, both subjects of the Queen of Great Britain, residing at Laurvig, in the Kingdom of Norway, have invented certain new and useful Improvements in Percussive Rock-Drills, (for which we have obtained a patent in Great Britain, No. 3,691, bearing date 10 March 2, 1889,) of which the following is a specification.

Our invention relates, first, to improvements in the class of percussive rock-drills described in the specification of our prior patent, No. 15 389,740, dated September 18, 1888; and it consists in an improved arrangement of the passages formed in the piston-rod for the purpose of actuating the valve of the drill-cylinder; second, to an improved arrangement of 20 parts, enabling the same machine to be fitted to different-sized saddles, according to the length of feed desired; third, to an improved feed for advancing the drill along the saddle, and, fourth, to an improved block or bearing 25 for fixing or combining the rotating gear and the feed-gear of the drill.

The second and third improvements are applicable to percussive rock-drills generally.

In the accompanying drawings, Figure 1 is 30 a longitudinal section of our improved drill. Fig. 1^a is a side elevation of the end cap or cover of the valve-piston cylinders; Fig. 2, a plan of Fig. 1 with covers of valve-chest and pawl-box removed; Fig. 3, a section 35 through valve-chest and main cylinder on line A B; Fig. 4, a section through the rotating gear on line C D; Fig. 5, a section on line E F, showing the automatic feed-gear; Fig. 6, a plan of valve-box cover; Fig. 7, a plan of 40 valve-box with cover removed; Fig. 8, a plan of pawl-box cover; Fig. 9, a section through G H; Fig. 10, a plan of valve; Fig. 11, a longitudinal section of saddle; Fig. 12, a plan of saddle; Fig. 13, a transverse section of a saddle on line I J; Fig. 14, a transverse section 45 of a modified form of feed-gear; Fig. 15, a horizontal section of the puppet-head of the feed-gear shown, and Fig. 16 a horizontal section of a modified form of the link and pawl of 50 such puppet-head.

In carrying out the first improvement re-

ferred to we construct the passages M M² in the piston-rod R R' R² of such length that when the piston P is near the end of its backward stroke one end of the passage M² comes 55 outside the stuffing-box, through which such rod works into the upper part of the cylinder, which is open to the atmosphere, while the other end of such passage M² is opposite the passage M³, formed in the stuffing-box, and 60 which (as described in our patent above referred to) leads to the end of the valve-cylinder C', so that such end of the valve-cylinder will be directly open to exhaust to the atmosphere at the time that compressed air 65 or steam is admitted to the other end C² of such valve-cylinder in order to reverse the valve V. Similarly when the piston P is near the end of its forward stroke one end of passage M is outside the stuffing-box 70 or open to the atmosphere, while its other end is opposite the passage M' in the stuffing-box and leading to the end C² of valve-cylinder, so that such end C² will be directly open to exhaust to the atmosphere at the time that 75 compressed air or steam is being admitted to the other end C' of valve-cylinder, in order to reverse the valve V. The action described occurs at each end of the piston-stroke, thus rendering the reversal of the valve V certain 80 by enabling any accumulation of the motive fluid which may take place at one end of the valve-cylinder to be exhausted into the atmosphere during the action of reversing the valve V. Any suitable number of openings 85 O' may be made from the ends of the passages M M² to the outer surface of the piston-rod. When the valve-pistons P' P², which are connected together by stem D' and between which the valve V is arranged, are caused to move 90 in their cylinders C' C², they will carry valve V with them, and so control the movement of piston P in cylinder C by governing the supply and exhaust passages I I E thereof.

Our second and third improvements, which 95 are applicable to percussive rock-drills generally, consist in a novel construction of parts for effecting the automatic feed or advance of the machine along the saddle as the hole is bored by the drill and which enables the 100 same machine to be mounted on different-sized saddles, according to the length of feed

required. The saddle consists of a bed D, of segmental section, and having at its center the saddle-arm D², by which it is connected to a carriage or column, while at each end is a vertical plate D³. These two plates D³ are connected together by two longitudinal bars Q', one at each side, with which four arms Q², projecting down from the drill-casing B, engage, so that the bars serve to guide the machine in its movement in relation to the saddle. The feed-screw Q is arranged between the guide-bars Q', and is provided with a crank-handle for effecting the return movement of the machine in the usual manner after it has been automatically fed forward to the full extent on the saddle. A spring catch or pin T² is arranged to fit in a suitable hole or recess in the screw, so as to prevent it rotating when the machine is being fed forward automatically. The feed-nut N is mounted on the feed-screw Q, and is carried in bearings forming part of or secured to the drill-casing B, in which such nut can rotate. By this arrangement, as the guide-bars Q' and feed-screw Q are carried by the saddle, while the arms Q², to engage the guide-bars, and the feed-nut N are carried by the machine, the latter may be mounted on any saddle, the bars and feed-screw of which may be of any desired length, but of a diameter and relative disposition suitable to engage the guide-arms Q² and feed-nut N on the machine. On the end of the feed-nut N a ratchet-wheel Z is attached or formed and is provided with ratchet-teeth. A puppet head or slide P² has two arms J J' working through guide-holes L² in, or bearings outside, the body of the drill-casing B, one of such arms having an opening S' to receive a spring G', which is fitted to react against an arm H, fitting therein, and either projecting from the drill-casing or the cap used to cover the bearing. The spring G' tends to force the puppet head or slide against an inclined lifter L. The puppet head or slide P² has a part K, which lies in the direct path of the drill-piston rod R' R² as it reciprocates, and on such piston-rod R' R² the inclined lifter L is formed or arranged, the inclined surface acting upon the part K of the puppet-head and forcing the same outward during the backward stroke of the drill. In order to permit the drill to be rotated after each stroke, the connection between its piston-rod R² and the inclined lifter L may be in the form of the swivel-joint D⁴ C³ or of a ball or other suitable joint.

In the construction shown in Figs. 14 and 16 the part of the puppet-head below the lifter L has pivoted thereto a link W, the end of which is in the form of a pawl H' and shaped to engage the ratchet-teeth, which in this case are formed on the end face of the wheel Z², forming part of the feed-nut N. The pivot W' of the link W extends through the puppet-head, and is surrounded by a spring G², tending to force the pawl H' toward or against the

ratchet-teeth. Instead of the spring G² being applied to the pivot W' of the link, as shown in Fig. 16, the part thereof which forms the pawl H' may be capable of sliding through the body of the link W, and the spring G², arranged to force such sliding part H' into contact with the ratchet-teeth of the feed-nut, as shown in Fig. 15. When in action the lifter L moves with the drill-spindle and piston, and accordingly raises and lowers the puppet-head P³, the action of the spring in the interior of arm J thereof reacting against projecting arm H, insuring the return movement of the puppet-head during the forward stroke of the drill. The reciprocating motion thus imparted by the drill-spindle to the puppet-head P³ is communicated to the link-pawl W, which, moreover, acquires a lateral and an angular motion in the performance of its functions, the former by the detent of the link sliding over the inclined planes of the teeth of the ratchet-wheel Z² of the feed-nut N and the latter by its being compelled to move in the circular path of the ratchet-teeth. The pivoted connection between the link W and the puppet-head P³, together with the spring acting upon such pivot, (or upon the sliding part working through the body of the link,) permits these movements. The teeth of the ratchet-wheel are semicircular, and the length between them is so proportioned as not to allow the pawl H' to engage the next tooth before the piston has made its full forward stroke. When this takes place, the pawl H' is forced into engagement with one of such notches or teeth by the spring G² acting upon its pivot, (or upon the sliding part,) and, owing to the forward movement of the pawl which follows, a partial rotation of the ratchet-wheel Z² is effected on the return or back stroke of the piston P, such movement being transmitted to the feed-nut N, which turns on the feed-screw Q, and thus forces the machine forward on the saddle. In consequence of this advance the next stroke of the piston P will not be a full stroke, and will not be a full stroke again until the length of the forward movement has been bored by the drill, and until this takes place the pawl cannot enter a fresh notch or tooth of the ratchet-wheel. Immediately that the piston regains its full stroke the pawl will engage a fresh notch or tooth and a further advance will be given to the machine. The inclined lifter L cannot rotate with the drill-spindle R' R², as it is always in contact with the rubbing-surface of the puppet-head P³, the pressure by which the surfaces are kept together by the spring G' in the interior of arm J of puppet-head P³ being more than sufficient to counterbalance the friction of the swivel attachment D⁴ C³ between the lifter L and the drill-spindle R' R². Moreover, such rotation is entirely prevented by causing the lifter to work through the puppet-head P³, as shown. The lifter L is further preferably provided with guide sur-

faces or webs engaging suitable grooves, which serve to guide it in its to-and-fro movement with the piston-rod.

In the modified construction of feed-gear shown in Figs. 1 and 5 the arm J' of the puppet-head P³ carries the pawl H' in the guide-socket S², wherein the spring G² is fitted to react upon the pawl H', so as to force it in contact with the inclined planes of and (when the drill-piston has made its full stroke) to engage the teeth of the ratchet-wheel Z, secured to feed-nut N, mounted on the feed-screw Q, the teeth of such ratchet-wheel Z being in this case formed on the periphery thereof instead of on its end face, as in the arrangement previously described. The other arm J of the puppet-head or slide P³ has an opening S' in its outer end to receive the spring G', and the arm H, mounted on the casing B of the drill or forming part of the cap of bearing B², enters the opening S', so as to cause the reaction of spring G' on the puppet-head P³, as in the arrangement already described. When lifter L moves with the drill-piston P during its back-stroke, its inclined surface forces the puppet-head P³ against the action of the spring G', and the pawl H', gearing with ratchet-wheel Z, rotates the same, so as to effect the feed. During the forward stroke of the drill spring G' forces the puppet-head P³ in the opposite direction, causing the pawl H' to slip over the teeth of ratchet-wheel Z and to engage a fresh tooth thereof, when the piston again attains its full stroke in the same manner as before described.

The feed-gear can be adapted to either end of the drill. In applying the gear to the forward end of the drill a collar will be secured to the drill-piston rod, so that such collar will follow this latter in its to-and-fro movements, while permitting the piston-rod to turn within it, and to this collar the lifter L will be secured, and by its to-and-fro movements will actuate the feed-gear in the manner above described.

The fourth improvement consists in the method of providing a bearing for the end of the rifled bush Y of the rotating gear in the block or bearing F', (see Fig. 1,) and causing such block to serve as a guide for the piston-rod R² and the inclined lifter L. The bearing or block F' in its longitudinal section has the form of a cone, except at each end, where it is provided with a circular plate B'. A circular opening passes through the center of

the block F' to allow of the travel of the piston-rod R² and lifter L, for which it acts as a guide. The plates B' at each end are accurately turned on their circular edge to fit compactly against the interior of drill-casing, and the whole is fixed in the position shown in Fig. 1 by screw-bolts E', (shown in Fig. 5,) one half section of each of which is in the block and the other half in casing of drill. The forward end of the rifled bush Y for rotating the drill at each backward stroke of the piston has its bearing in the rear end of the block or bearing F'.

What we claim as our invention, and desire to secure by Letters Patent, is—

1. The combination of the drill-casing, the valve-chamber connected therewith and containing the steam-valve, passages M' and M³, connecting opposite ends of said valve-chamber with the drill-casing, a piston-rod within said casing provided with a piston P and with elongated passages M and M² on opposite sides of said piston, the passage M, registering at one end with the outer atmosphere and at the other end with the passage M' when the piston is near the end of its forward stroke, and the passage M², registering at one end with the outer atmosphere and at the other end with the passage M³ when the piston is near its backward stroke, substantially as set forth.

2. The combination, in a rock-drill, of a saddle carrying the guide-bars and feed-screw, with a nut mounted to revolve in the casing of the drill and engaging the feed-screw, while arms projecting from such casing engage the guide-bars, all substantially as and for the purpose specified.

3. The combination, with the piston-rod, of a cuneiform or wedge-shaped lifter for actuating the feed-gear, said lifter being adapted to reciprocate with the piston-rod and prevented from rotating therewith, substantially as described.

4. The combination, with the drill-casing, of a hollow block F', the drill-piston extending into said block, a lifter L, guided in said block and connected to said piston, a puppet-head actuated by said lifter, and a bush Y, journaled at one end in said block, substantially as described.
